AIR COOLED MUFFLER

John S. Fluor, Jr. and Park W. Ash, Santa Ana,
Calif., assignors to The Fluor Corporation Ltd.,
Los Angeles, Calif., a corporation of California

Application May 4, 1936, Serial No. 77,821

15 Claims.

(Cl. 60—31)

This invention relates generally to mufflers for large stationary engines, for example of the type used in natural gas compressor plants, and has to do particularly with improvements in mountings for air cooled mufflers of that type.

In the general structure which embodies the mounting, the muffler is supported within a stationary shell or stack that is annularly spaced from the muffler to provide a passage through which the muffler cooling air is drawn. Usually an exhaust pipe of considerable length is connected to the muffler, and due to expansion and contraction of the exhaust pipe resulting from its temperature changes, the muffler is caused to shift considerably within the surrounding shell. The general purpose of this invention is to provide in conjunction with a muffler and shell, a mounting that will permit such shifting movement of the muffler and yet maintain it at all times in proper position relative to the outer shell.

More specifically, one of our major objects is to provide in combination with the muffler and shell, a mounting that will permit lateral movement of the muffler within the shell without allowing the muffler to tilt or swing from its normal position of parallelism with the shell. By this type of mounting, we are able to maintain the muffler outlet and the path of flow of the combustion gases being discharged from the outlet, at all times in parallel with the shell outlet, thereby eliminating eddy currents and any back pressure within the air passage, that would otherwise result from tilting of the muffler. Thus the invention is an improvement over tilting or pivotal type mountings as disclosed in Patent No. 1,966,620 issued to John S. Fluor, Jr., July 17, 1934, on Muffler, wherein the muffler is pivotally suspended for oscillating movement about a pair of trunnions located intermediate the ends of the muffler.

In its preferred form, the invention comprises a two point suspension supporting the muffler at its upper end and embodying means permitting both longitudinal and lateral bodily movement of the muffler within the shell. The individual suspensions include springs that vertically support the muffler, and are mounted for straight lateral shifting movement in a plane normal to the longitudinal muffler axis. Preferably, we also include yielding means resisting lateral movement of the muffler in a direction at right angles to the path of movement permitted by the vertical suspensions, so that the muffler is yieldably supported both vertically and laterally.

The various objects and features of the inven-

tion mentioned in the foregoing, together with various additional aspects thereof, will be better understood from the following detailed description of the invention in one of its typical and preferred forms. Throughout the description reference is had to the accompanying drawing in which:

Fig. 1 is a general elevation, partly in section, showing a typical form of muffler installation;

Fig. 2 is an enlarged horizontal cross section on line 2—2 of Fig. 1, (the sectional view being turned 90° from the aspect of Fig. 1) showing the muffler suspensions in plan; and

Fig. 3 is an enlarged fragmentary section on line 3—3 of Fig. 2 showing one of the individual suspensions in detail.

First it is to be understood that the present type of muffler mounting may be applied to various forms of mufflers arranged for connection with the exhaust pipe in any of the usual manners. For the purpose of illustrating a typical air cooled muffler installation in which the muffler is subject to shifting movement within a stack or outside shell, we have shown in Fig. 1 a diagrammatically illustrated internal combustion engine 10 within the engine room 11 and having an exhaust pipe 12 extending downwardly and then horizontally within a trench 13 below the room floor 14. Exhaust pipe 12 connects at its outer end with a vertically extending muffler 15 which may be of any suitable design and construction. The muffler is mounted on the hereinafter described suspensions, generally indicated at 16, within a vertically extending stack 17, the shell 18 of which is annularly spaced from the muffler to provide an air passage 19. The muffler outlet 20 projects upwardly within tapered portion 21 of the stack, the constriction formed by the latter causing air to be drawn upwardly through space 19 by the velocity effect of the combustion gases being expelled from the muffler, and the gas and air mixture to be discharged to the atmosphere through the top 22 of the stack.

The exhaust pipe is jacketed by an air conduit 23 having an inlet 24 opening upwardly through the floor 14 within the room 11, and connected at its outer end to the stack 18 by a joint at 25. Stack 18 and conduit 23 together form a cooling air jacket about the exhaust pipe and muffler, and into which air is drawn from the room 11 into inlet 24, and thence through passages 26 and 19 to be finally discharged through the stack. As illustrated in Fig. 1, frequently the exhaust pipe 12 is rather long, so that when the temperature of the pipe changes, as at the time the engine

is started or stopped, it has considerable longitudinal expansion and contraction. As a result, the muffler 15, being rigidly connected at 27 to the exhaust pipe, is required to shift laterally within the stack 18 in response to expansion or contraction of the pipe. One of the major features of the invention is the provision of a mounting for the muffler that will permit such lateral shifting of the muffler and yet maintain it at all times in a true vertical position, i. e., with the longitudinal axis of the muffler remaining parallel with the corresponding axis of the stack.

Our improved mounting is of a two point suspension type in which the individual suspensions 16 are located at diametrically opposite sides of the muffler and, where the exhaust pipe leads into the side of the muffler as in the illustrated form, the suspensions lie in a plane normal to the exhaust pipe and therefore normal to its direction of expansion and contraction. Referring now to Fig. 3, each of the individual suspensions 16 comprises a bracket support 28 welded to the shell 18 and having a top flat surface 29 extending horizontally in a plane normal to the muffler axis. The muffler is vertically supported by a coil spring 30 resting on surface 29 and shiftable horizontally thereon, the length of surface 29 being sufficient to permit shifting movement of the spring within the limits of the transverse muffler movement caused by expansion or contraction of the exhaust pipe. Spring 30 is placed about the lower end of a bolt 31 extending through a member 32 projecting laterally beyond the muffler shell, the bolt being held in adjusted position by nuts 33 and 34. Member 32 is welded to the muffler at 35, and is secured by bolt 36 to the muffler top wall 37.

A second coil spring 38, placed about the upper end of bolt 31, is confined between nut 33 and a support 39 of angular cross section, secured to shell 18 by bolts 40. As will appear from Fig. 2, the bolt and spring assembly is permitted to shift in the direction indicated by the arrows, within the limits of engagement with the angular depending end walls 39a of supports 39. The parts of the spring suspension rigidly attached to the muffler thus are yieldably confined against vertical movement in both directions between the stationary supports 28 and 39, and the muffler is permitted to move vertically within the shell with the springs acting to absorb any vibration and eliminate vibratory noises. Access may be had to nuts 33 and 34 for the purpose of adjusting them to regulate the compression of springs 30 and 38, through a shell opening 41 that is normally closed by cover plate 41a.

Lateral movement of the muffler in a direction at right angles with its path of shifting movement as permitted by the vertical spring supports, is yieldably resisted by springs 42 placed about bolts 43 welded to and projecting from diametrically opposite points on the muffler outlet pipe 20. Springs 42 are held against the vertical surfaces 39b of supports 39 by adjustable nuts 44, to guide the muffler for movement parallel to surfaces 39b, the springs being shiftable along these surfaces as springs 30 are subjected either to vertical compression or horizontal shifting on their supports. And at all positions, springs 42 effectively resist and absorb transverse muffler vibration permitted by lateral movement of the exhaust pipe.

It is believed that the functions and operation of the support will be fully apparent from the foregoing. As the exhaust pipe 12 expands or

contracts, corresponding lateral movement of the muffler is permitted by the capacity of the vertical suspensions (bolts 31 and springs 30 and 38) to shift horizontally between supports 28 and 39 in the directions indicated by the arrows (Fig. 2). At the same time, springs 42 shift correspondingly along surfaces 39b. Being positioned as indicated, the assembly of springs yieldably supports the muffler both vertically and transversely, and effectively absorbs all vibratory movement of the muffler within the stack.

We claim:

1. In a stationary engine plant, the combination comprising an elongated muffler, an exhaust pipe connected to the muffler and extending laterally relative thereto so that the muffler shifts laterally as the exhaust pipe expands and contracts longitudinally, a conduit surrounding the muffler and annularly spaced therefrom to provide an air passage, and means supporting said muffler within said conduit, said supporting means permitting lateral bodily movement of the muffler relative to the conduit in response to longitudinal expansion and contraction of the exhaust pipe, and including means for causing both ends of the muffler to shift the same distance and in the same direction during said lateral movement of the muffler.

2. In a stationary engine plant, the combination comprising an elongated muffler, an exhaust pipe connected to the muffler and extending laterally relative thereto so that the muffler shifts laterally as the exhaust pipe expands and contracts longitudinally, a conduit surrounding the muffler and annularly spaced therefrom to provide an air passage, and yielding means supporting said muffler within said conduit, said supporting means permitting lateral bodily movement of the muffler relative to the conduit in response to longitudinal expansion and contraction of the exhaust pipe, and including means for causing both ends of the muffler to shift the same distance and in the same direction during said lateral movement of the muffler.

3. In a stationary engine plant, the combination comprising an elongated muffler, an exhaust pipe connected to the muffler and extending laterally relative thereto so that the muffler shifts laterally as the exhaust pipe expands and contracts longitudinally, a conduit surrounding the muffler and annularly spaced therefrom to provide an air passage, means supporting said muffler within said conduit, said supporting means permitting lateral bodily movement of the muffler relative to the conduit in response to longitudinal expansion and contraction of the exhaust pipe, and including means for causing both ends of the muffler to shift the same distance and in the same direction during said lateral movement of the muffler, and yielding means resisting said lateral movement.

4. In a stationary engine plant, the combination comprising an elongated muffler, an exhaust pipe connected to the muffler and extending laterally relative thereto so that the muffler shifts laterally as the exhaust pipe expands and contracts longitudinally, a conduit surrounding the muffler and annularly spaced therefrom to provide an air passage, and means supporting said muffler within said conduit, said supporting means including yielding means permitting longitudinal movement of the muffler within the conduit, and yielding means resisting lateral movement of the muffler relative to the conduit.

- in response to longitudinal expansion and contraction of the exhaust pipe.
5. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, yielding means supporting said muffler within the conduit, and yielding means resisting lateral movement of the muffler relative to said conduit. 10
6. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, and horizontally and bodily shiftable yielding means supporting said muffler within the conduit. 15
7. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, horizontally and bodily shiftable yielding means supporting said muffler within the conduit, and yielding means resisting lateral movement of the muffler relative to said conduit. 20
8. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, a muffler supporting member on said conduit, a supported member associated with said muffler and bearing on the first mentioned member and shiftable horizontally thereon. 25
- 40
9. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, a muffler supporting member on said conduit, a spring bearing on said member and shiftable horizontally thereon, and means for supporting the muffler on said spring. 45
10. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, a supporting member having a bearing surface extending in a plane normal to the longitudinal axis of the muffler, and a muffler supporting
- member bearing on said surface and shiftable horizontally thereon to permit lateral movement of the muffler within said conduit. 5
11. In a stationary engine plant, the combination comprising a vertically extending muffler shell, an exhaust pipe connected to the muffler and extending horizontally so that the muffler shifts laterally as the exhaust pipe expands and contracts, a conduit surrounding said muffler and annularly spaced therefrom to form an air passage, and a muffler suspension comprising a support on said conduit, and muffler supporting means secured to the top portion of said shell and bearing on said support. 10
12. In a stationary engine plant, the combination comprising a vertically extending muffler shell, an exhaust pipe connected to the muffler and extending horizontally so that the muffler shifts laterally as the exhaust pipe expands and contracts, a conduit surrounding said muffler and annularly spaced therefrom to form an air passage, and a muffler suspension comprising a support on said conduit, and muffler supporting means secured to the top portion of said shell and bearing on said support, said means being shiftable horizontally on said support. 15
13. In a stationary engine plant, the combination comprising a vertically extending muffler shell, an exhaust pipe connected to the muffler and extending horizontally so that the muffler shifts laterally as the exhaust pipe expands and contracts, a conduit surrounding said muffler and annularly spaced therefrom to form an air passage, and a muffler suspension comprising a support on said conduit, and muffler supporting means secured to the top portion of said shell and bearing on said support, said means comprising a spring shiftable horizontally on said support. 20
14. In a stationary engine plant, the combination comprising a vertically extending muffler shell, an exhaust pipe connected to the muffler and extending horizontally so that the muffler shifts laterally as the exhaust pipe expands and contracts, a conduit surrounding said muffler and annularly spaced therefrom to form an air passage, a muffler suspension comprising a support on said conduit, and muffler supporting means comprising a spring shiftable horizontally on said support, and yielding means resisting lateral movement of the muffler within said conduit. 25
15. In a stationary engine plant, the combination comprising a vertically extending muffler, an exhaust pipe connected to the muffler and extending horizontally so that the muffler shifts laterally as the exhaust pipe expands and contracts, a conduit surrounding said muffler and annularly spaced therefrom to provide an air passage, means supporting said muffler for lateral movement within the shell in one direction, and yielding means resisting lateral movement of the muffler in a direction at right angles with the first mentioned direction. 30
